UNITED STATES PATENT OFFICE.

GEORGE D. HART, OF MUNCY, PENNSYLVANIA.

IMPROVEMENT IN CULTIVATORS.

Specification forming part of Letters Patent No. 78,203, dated May 26, 1868; antedated May 11, 1868.

To all whom it may concern:

Be it known that I, GEORGE D. HART, of Muncy, Lycoming county, State of Pennsylvania, have invented a new and useful Improvement on a Cultivator or Corn-Plow, originally secured by Letters Patent dated 2d day of April, 1867, No. 63,384; and I do hereby declare that the following is a full, clear, and exact description of the construction and operation of the same, reference being had to the annexed drawings, making a part of this specification, in which—

Figure 1 is a perspective view. Fig. 2 is a reverse view of the plate securing the standards to the under part of the frame of said machine. Fig. 3 is a view of the standards when detached from the plate No. 2. Fig. 4 is a perpendicular front view, showing the combination of three standards instead of two, as in the original machine.

Letters *a b* show the plate as connecting the standards with the frame. *c c* represent the manner in which the tops of the standards are secured in plate. Letter *d* shows the flange or hook by which the standard is connected with plate; *e e*, in Fig. 4, the same as *d* in Fig. 3, the third arm in this drawing, and the hooks and flanges on the two back standards for securing them more firmly to the plate, as described by Fig. 2; also said plate.

The above as set forth is what I claim as my invention, whether used in combination with this machine or separate in any other, reference being had to Letters Patent above referred to.

GEO. D. HART.
